2 SHEETS—SHEET 2.

UNITED STATES PATENT OFFICE.

WILSON R. MYERS, OF PORTLAND, OREGON, ASSIGNOR OF ONE-HALF TO GEORGE W. BURT, OF PORTLAND, OREGON.

ICE-DELIVERY MECHANISM.

Application filed December 6, 1920. Serial No. 428,680.

To all whom it may concern:

Be it known that I, WILSON R. MYERS, a citizen of the United States, residing at Portland, in the county of Multnomah and 5 State of Oregon, have invented certain new and useful Improvements in Ice-Delivery Mechanism, of which the following is a specification.

My invention relates to certain new and 10 useful improvements in ice delivering hoppers, especially adapted for use in connection with machinery for icing ice cream tubs, such for example as shown in my copending application Serial No. 376,185, filed 15 April 24, 1920, and the present invention has for its object to provide a hopper construction with delivering mechanism and agitators so arranged that the delivering of the crushed ice will be facilitated and banking 20 or bridging of ice in the hopper and conveyer duct will be positively avoided.

In its generic nature, the invention comprises a hopper consisting of a bottom portion having downwardly converging side 25 walls connected with a concaved feed-way that delivers into the delivery spout, that portion of the hopper above the inclined bottom walls being gradually constricted toward the top, whereby the opening of the 30 hopper in which the crushed ice is poured is of less cross sectional area than that portion of the hopper adjacent to the inclined bottom; within the concaved feed-way is a propeller which forces the crushed ice to the 35 outlet duct and above the propeller and parallel thereto is an agitator, the arms of which project downwardly adjacent to the shaft of the propeller so as to operate between the rotating blades of the propeller 40 and thus prevent an ice bridge across the concaved feed-way, there being another agitator mounted in the upper part of the hopper with its axis transverse with respect to the feed-way, so as to prevent bridging of 45 the ice in the upper part of the hopper; wall scrapers are also provided in the hopper for scraping the inclined bottom walls of the same, the wall scrapers being connected together so as to oscillate in opposite directions for convenience and the several agitator shafts and the scrapers may be provided with handles by which they may be 50 manually operated or, as my invention provides, mechanical means may be employed to effect the operation of the several parts.

In its more detailed nature, the invention also resides in those novel features of construction, combination and arrangement of parts, all of which will be first fully described, and then be specifically pointed out 60 in the appended claims, reference being had to the accompanying drawings, in which:

Figure 1 is a top plan view of the invention.

Figure 2 is a rear elevation of the same 65 on a reduced scale.

Figure 3 is a central vertical longitudinal section of the invention, the propeller and the agitator cooperating therewith being shown in elevation.

Figure 4 is a central vertical cross section 70 of a portion of the hopper, the transverse agitator being shown in elevation.

In the drawings in which like numerals of reference indicate like parts in all of the 75 Figures, 1 is the hopper which is preferably provided with an insulated outer wall 2 to prevent a too rapid transfer of heat into the hopper.

3 indicates the inclined bottom walls of 80 the hopper, which connect with the concaved feed-way 5 in which the propeller operates. The propeller consists of a shaft 6 with suitably directed blades 7 so arranged as to tend to force the material toward the outlet duct 85 or throat 4.

8 is the agitator shaft which extends parallel to the shaft 6 and has its fingers 9 so designed as to project down within the path of rotation of the propeller to operate between adjacent propeller blades, as best 90 shown in Figures 3 and 4 of the drawings.

The shaft 8 may be squared at 10 to receive a suitable crank 11, by which it may be operated manually, if desired.

I prefer, however, to drive the agitator shaft 8 from the propeller shaft 6 or from some other suitable part of the apparatus, the driving connection between the propeller shaft 6 and the agitator shaft 8 being illustrated as a gear connection 12.

13 is the upper agitator whose arms 14 are suitably spaced apart and which also has a squared portion 15 to receive a suitable crank 16, by which it may be turned.

I prefer, however, as before stated, to drive all of the moving parts mechanically and, to this end, the shaft 13 may be driven from the first motion shaft 21 in any suitable way, as for example by means of beveled 110

gears 17—18, shaft 19, beveled gears 20 (see Figures 1, 2 and 4).

The propeller shaft 6 may be driven from the first motion shaft 21 by suitable sprocket 5 and chain connection 24—23—23, best shown in Figures 1 and 3 of the drawings.

25 designates scraper bars which are provided with scraper arms 26 and handles 27, the arms 26 lying in contact with the inclined walls 3 of the hopper so that, when the bars 25 are reciprocated, the arms 26 will scrape the frozen material from the inclined walls, if such there be.

I prefer, however, to operate the bars 25 mechanically and this may be done through a connecting lever 29 fulcrumed at 30 to a bracket and pivoted at 28 to the bars 25, the connecting bar 29 being oscillated by a bell crank whose long arm 33 engages the bar 29 and whose short arm 31 is connected by a pitman 34 with a suitable cam device 35, by which the necessary reciprocating motion may be imparted.

While I have shown one specific embodiment of my invention, I desire it understood that modifications of the same in the arrangement of parts and details of construction may be made without departing from the spirit of the invention or the scope of 30 the appended claims.

What I claim is:

1. In ice delivery mechanism, a hopper having an entrance and having sides diverging downwardly from the entrance, said 35 hopper having a bottom consisting of converging side walls leading to a concavity, a propeller located in said concavity, said hopper having a discharge throat to which said propeller delivers the contents, an agi-

tator cooperating with the propeller for preventing ice bridges adjacent to the propeller, reciprocating scraper bars operating over the converging walls of the hopper, means for rotating the propeller and agitator, and means cooperating with said rotating means 45 for translating the rotary motion into a reciprocatory motion and reciprocating said scrapers.

2. In ice delivery mechanism, a hopper having inclined bottom walls and a bottom feed trough, a feed propeller in said feed trough, scrapers in the hopper operating over the inclined walls to dislodge the ice from the inclined walls, an agitator shaft in the bottom of the hopper paralleling the feed propeller and having radial arms projecting into the path of rotation of the propeller between the blades thereof for preventing ice bridges.

3. In ice delivery mechanism, a hopper comprising an upper section and a lower section, the lower section comprising inclined bottom walls and a feed trough having a discharge outlet, the upper portion of the hopper having its walls converging toward the top, whereby the entrance to the hopper is of less cross sectional area than that portion adjacent to the inclined walls, a propeller mounted within the feed trough for forcing the ice to the outlet opening, means within 70 the hopper for agitating the ice to prevent the formation of ice bridges, scrapers mounted in the hopper on the inclined walls for loosening the ice from the inclined walls, and means for operating said propeller, said 75 agitators and said scrapers.

WILSON R. MYERS.
